(57) **CLAIM**

The ornamental design for a housing for a plurality of cameras, as shown and described.

DESCRIPTION

FIG. 1 is a perspective view of a housing for a plurality of cameras showing my new design;

FIG. 2 is a front elevational view thereof;

FIG. 3 is a right side elevational view thereof, the undisclosed left side elevational view being a mirror image of the right side;

FIG. 4 is a rear elevational view thereof;

FIG. 5 is a bottom plan view thereof; and,

FIG. 6 is a top plan view thereof.

The broken lines in the figures are for illustrative purposes only and form no part of the claimed design.
